(57) **CLAIM**

The ornamental design for a tamper-evident container, as shown and described.

DESCRIPTION

FIG. 1 is a perspective view of a tamper-evident container of my design.

FIG. 2 is a back view of the tamper-evident container of FIG. 1;

FIG. 3 is a front view of the tamper-evident container of FIG. 1;

FIG. 4 is a side view of the tamper-evident container of FIG. 1;

FIG. 5 is a side view of the tamper-evident container of FIG. 1;

FIG. 6 is a top view of the tamper-evident container of FIG. 1; and,

FIG. 7 is a bottom view of the tamper-evident container of FIG. 1.

The dashed lines shown represent portions of the tamper-evident container that form no part of the claimed design.

1 Claim, 7 Drawing Sheets
